UNITED STATES PATENT OFFICE

JOSEPH M. HURLEY, OF MINNEAPOLIS, MINNESOTA

FILE INDEX DEVICE

Application filed October 25, 1930. Serial No. 491,208.

This invention relates to file index devices.

It is the main object of the present invention to provide a device which can be quickly and conveniently used for gathering memoranda, classifying the same, indexing the same and filing the same.

It is a further object to provide a file index of novel and improved construction, whereby memoranda sheets can be quickly and conveniently filed away for record; the position of the sheets can be rapidly changed and the sheets can be quickly and easily removed for convenient use at other points than where the file index is located.

To these ends, the invention consists in the novel parts and novel combinations of parts, hereinafter defined in the claims and described in the following specification, made in connection with the accompanying drawings, wherein like reference characters refer to the same or similar parts throughout the various views, and, in which,

Fig. 1 is a plan view illustrating the complete file index, the envelopes of the index being indicated in full lines in downwardly swung position, and in dotted lines in upwardly swung position;

Fig. 2 is a view similar to Fig. 1, but illustrating the envelopes in upwardly swung position;

Fig. 3 is a view on an enlarged scale illustrating one corner of the index device, the envelopes and wires being removed;

Fig. 4 is a vertical section taken on the line 4-4 of Fig. 3, as indicated by the arrows, a wire and an envelope carried thereby being illustrated;

Figs. 5, 6 and 7 are views in side elevation illustrating three different types of housing members that may be used;

Fig. 8 is a vertical section taken through one of the envelopes that may be used, the thickness of the material forming the envelope and sheets carried thereby, being greatly exaggerated; and

Fig. 9 is a vertical section taken through one of the flaps of the envelope, the thickness of the material forming the envelope being even more greatly exaggerated than in Fig. 8.

Referring to the drawings, in accordance

with the present invention there is provided a panel 10 which serves as a base or support upon which a pair of spaced parallel channel-shaped guides 11 are mounted. The guides are so disposed that their open sides face each other and if the panel 10 is considered to be disposed in a horizontal plane, each guide 11 may be considered to include a horizontal base flange secured to the panel 10 as by rivets 12, an outer vertical flange and an upper and inwardly projecting horizontal flange. The base flange of each channel is preferably of considerably greater width than the upper flange, as best shown in Fig. 4, and is reversely bent upwardly upon itself at its inner edge to form a recess within which the outer portion of a light plate-like spring 13 is seated. The springs 13 extend parallel to the guides 11 and their outer edges are free and are bent upwardly to normally lie adjacent the open sides of the two guides 11 and some little distance above the base flanges thereof. The free edges of the springs 13 are, however, compressible downwardly against the base flanges of the guides. Housing members 14 of various lengths, as shown in Figs. 5, 6 and 7, are adapted to be held in place within the guides 11. These housing members, although they may be made of various lengths as stated, each include an inner vertical side 14a having one or more vertical slots 15 cut therein. Joining the upper edge of the vertical side 14a of each housing member, is an upper horizontal flange 14b which is adapted to fit over the upper horizontal flange of one of the guides 11 and this flange serves as a handle or means for moving the housing member in the guide. The lower edge of the vertical flange 14a has joined thereto a horizontal and outwardly projecting base side 14c, which is adapted to fit against the outer portions of the base flanges of the guides below the upper horizontal flanges thereof. An upwardly projecting outer side 14d of the housing member

joins the outer edge of the base 14c and is adapted to extend against the vertical flange of the guides and to a point slightly below the level of the upper horizontal flanges thereof. End wings 14e join the edges of the inner

vertical side 14a of each housing member and these wings are adapted to project outwardly within the channels of the guides and in slightly downwardly spaced relation from the lower surfaces of the upper horizontal flanges of the guides. The housing members may be inserted in place in the guides 11 by placing them on the springs 13 and pressing the housing members downwardly to depress the springs 13 against the base flanges of the guides and then pushing the housing members outwardly. There is sufficient clearance between the upper edges of the wings 14e and the outer sides 14d of the housing members 15 to permit insertion of the wings 14e, side 14d and base 14c of the housing members within the channels of the guides, while the springs 13 are depressed against the base flanges of the guides. After the housing members are 20 in place, the free edges of the springs 13 will, of course, rise to their normal position and the springs will act to retain the housing members within the guides. It will be seen that the housing members can be readily removed from the guides by merely pressing the springs downwardly and withdrawing the housing members from the channels of the guides. The guides 11 have downturned wings at their ends which prevent the housing 25 members 14 from being removed from the ends of the guides. Filler members 16 similar in all respects to the housing members 14, with the exception that no slots similar to the slots 15, are cut in the filler members, 30 may be used to take up the space in the guides not occupied by the housing members.

Attention should be called to the fact that the flanges 14b and the bases 14c of the housing members are notched at their inner edges 40 to form continuations of the slots 15. In practice, pairs of housing members 14 of the same length and having the same number of slots 15 cut therein, are disposed in the guides 11 in opposition to each other, so that the slots 15 in opposite housing members will lie in the same plane extending at right-angles to the panel 10 and transversely between the guides 11. Spring wires 17 are extended transversely between the two guides 45 11 and these spring wires have end portions which project into opposite housing members 14 through opposite slots 15 therein. The wires 17 are of such length that when inserted in place, the extreme ends of the wires 50 17 will almost strike the outer sides 14d of the housing members and these wires can be used alone without the springs 13 to hold the housing members in place in the guides 11. The spacing between the extreme ends of the wires 55 17 may be quickly reduced to insert or withdraw the wires from the housing members by merely bowing the wires or otherwise flexing the same. Preferably the extreme ends of the wires 17 will be sharpened or 60 pointed. Carried by the wires 17 are memo-

70 randa members 18 which may be envelopes as shown. These envelopes 18 are preferably of rectangular shape and have closed ends and one closed side, the remaining side being open as shown in Fig. 8 and in Fig. 2 and 75 there being inturned flaps 18a formed on both the top and bottom of the envelopes at the open side thereof. The corners of the envelope joining the closed side with the closed ends thereof, have small wire-receiving openings 18b therein which openings may be either left in the envelope at the time the envelope is formed, or may be punched therein by the ends of a wire 17 as the wire is inserted in place in the envelope. An envelope 18 may be applied to one of the wires 17 by inserting one end of the wire through one of the openings 18b at the closed corners of the envelope, then drawing the wire for some little distance through the opening until the opposite end of the wire is within the envelope and then sliding the said opposite end of the wire outwardly through the other opening 18b in the envelope. Preferably, the inner surface of the envelope 18 have carbon 80 layers 19 formed thereon, as shown in Fig. 9. Within the envelope, one or more reversely bent sheets 20 of paper may be disposed and one or more reversely bent carbon sheets 21 85 may be disposed between the sheets 20 of paper, if desired. The reversely bent sheets 20 and 21 will preferably be disposed within an envelope so that their edges will be underneath the flaps 18a, as shown in Fig. 8, and the eight portions of the sheets will be disposed adjacent the closed side of the envelope. 90 When the sheets 20 and 21 are used, the wires 17 will normally not be applied to the envelope until after the sheets 20 and 21 are in place, whereupon the eight portions of the sheets 20 and 21 will be disposed between the closed side of the envelope and the wire 17. The wire will thus divide the various sheets 20 and 21 into two sections and will tightly 95 hold the sheets in place to prevent unwarranted removal of the same. It will, of course, be understood that, if desired, the carbon layer 19 may be eliminated from the inner surface of the envelope 18, whereupon the sheets 20 may be made of transparent paper, if desired, and a carbon sheet 21 having carbon on both sides may be used between two or more sheets 20. It will be noted 100 that what may be called the top of the envelope projects a short distance beyond the bottom of the envelope at the free edge thereof. This is done so that an easy entrance is made for the fingers of a person handling the envelope between the top and bottom edges of the envelope for ready access to the interior of the same. The flaps 18a will, of course, hold the sheets 20 and 21 in place within the envelope whether or not the wire 17 is applied to the envelope. If the inner 105 110 115 120 125 130

surface of the envelope be provided with the carbon layer 19, the flaps 18a will also act to prevent the fingers of the person using the envelope from becoming soiled with carbon. For use in conjunction with the envelopes 18, a plate 22 formed from card board, metal or similar material, may be provided which may be inserted between the reversely bent portions of the inner sheets 20 carried by the envelope to serve as a backing and prevent impression made by a pencil or pen being carried more than midway through the laminations of the envelope when the sheets 20 and 21 are inserted therein.

With the present device, it will be seen that when a number of wires 17 carrying envelopes 18 are inserted in place between the housing members 14, the envelopes will all lie in overlapped relation either as shown in full lines Fig. 1, or in dotted lines Fig. 1, and in full lines Fig. 2. All the envelopes may be readily raised from the lower position shown in full lines Fig. 1, to the raised position shown in Fig. 2. The spacing between the various slots 15 in the housing members is such that the free edges of the various envelopes from top to bottom of the file index will project below the free edges of other envelopes and thus indexing data may be applied to the exposed portions of each envelope and this indexing data may be read at all times when the envelopes are inserted in place between the housing members. Any wire 17 carrying an envelope 18 may be quickly and readily removed or inserted in place by merely flexing the wires slightly. The wires also may be quickly removed from or applied to the envelopes, so that, if desired, any of the envelopes may be removed from the file index as for pocket use or may be again applied to the file index. The housing members 14 may be made of various lengths as shown in Figs. 5, 6 and 7, so that if desired, groups of envelopes disposed in the file may be separated from other groups of envelopes for classification purposes, and if desired, any number of envelopes may be grouped together by using housing members of the proper length and inserting these housing members at the proper positions in the guides 11. When one of the envelopes is written on, and two sheets 20 of paper with an interposed carbon sheet 21 are used, two duplicate carbon copies can be made of the matter written on the envelope by use of the plate 22, or, if desired, additional carbon copies or a less number of carbon copies can also be obtained. When a wire 17 is removed from an envelope 18, the various sheets in the envelope will be retained in the proper position by the wings 18a of the envelope and yet access can be readily had to these sheets for removal thereof from the envelope. By provision of the vertical slots 15 in the housing members 14, a wire 17 carrying a particular

envelope may rise to properly allow for the positioning of other envelopes below the same with the envelopes in overlapped relation and without causing the wires 17 to bind in the housing members. Also if desired, several wires 17 carrying envelopes 18 may be positioned in one pair of opposite slots 15 of a pair of housing members. By notching the flanges 14b of the housing members to cause the notches to join the slots 15, the position of the slots can always be readily observed to permit easy and quick insertion of the wires 17 in place within the slots. By making the springs 13 of light sheet material, it is possible to depress portions of the springs without depressing other portions thereof, so as to permit insertion or withdrawal of particular housing members 14 without removal of other housing members from the guides 11. The particular uses to which the file index device may be put is so varied, that no attempt will be made here to describe the same. All types of memoranda may be made on the various envelopes and sheets carried thereby and these memoranda may be classified, indexed and otherwise used as desired by use of the present device.

The present device has been successfully demonstrated in actual practice. The parts are few and simply constructed. Revision 95 of the file index may be quickly and easily made and envelopes may be quickly and easily inserted in place or withdrawn for use outside the file index device proper.

It will, of course, be understood that various changes may be made in the form, details, arrangement and proportions of the various parts without departing from the scope of the present invention.

What is claimed is:

1. A file index having in combination a backing panel, support housings mounted on said panel in parallel spaced relation, said housings having inner opposing sides with openings cut therethrough and each housing member having an outer imperforate side spaced outwardly a short distance from its inner side, spring wires having ends fitting within said openings, said wires being adapted to be flexed to release the same from said supports and memoranda members carried by said wires.
2. A file index device having in combination a backing panel, guides secured to said panel in parallel spaced relation, support housings mounted in said guides, resilient means for releasably clamping said housings in place on said guides, said housings having openings cut through their facing sides, spring wires having ends projecting through the openings in opposite housings, said wires being releasable from said housings by being flexed and memoranda members carried by said wires between said housings.
3. A file index device having in combina- 130

tion, a backing panel, a pair of guides mounted on said panel in parallel spaced relation, said guides being of channel shape and having their open sides facing each other, support housings mounted in said guides and having inner sides facing each other with openings therein, spring wires having their ends fitting within the openings of said housings and said wires extending between pairs of housings in opposite guides, said wires being of such length that their extreme ends will normally approximately strike the outer sides of said housings to retain said housings in said guides and said wires being releasable from said housings by being flexed and memoranda members carried by said wires between said housings.

4. A file index device having in combination, a backing panel, a pair of channel shaped guides applied in spaced parallel relation to said backing panel, the open sides of said guides being disposed toward each other, springs applied to said backing panel in inwardly spaced relation from said guides and having free edges normally projecting towards said guides and above the lower edges of said guides, housing members fitting within said guides and against the inner sides of which said springs are adapted to bear, said housing members having openings therein, spring wires having ends extending through the openings of oppositely disposed housing members and memoranda members carried by said wires between said guides.

5. A filing envelope for use in connection with a file index device, said envelope having both ends and one side closed and having its remaining side open and having small wire-receiving openings at its corners which join the closed ends and the closed side of the envelope, and inturned flaps on both top and bottom of the envelope at the open side thereof.

6. A filing envelope for use in a file index device, said envelope being of substantially rectangular shape and having its ends and one side closed and having its remaining side open, and having small wire-receiving openings at the two corners which join the closed ends and the closed side of the envelope, in-turned flaps on both top and bottom of the envelope at the open side thereof and carbon transfer material applied to the inner surface of the envelope.

7. A filing envelope for use in a file index device, said envelope being of substantially rectangular shape, having its ends and one side closed and having its remaining side open and having small wire-receiving openings at the two corners which join the closed ends and the closed side of the envelope, in-turned flaps on both top and bottom of the envelope at the open side thereof, a wire extending between the top and bottom of the envelope and through said wire-receiving

openings, carbon transfer material applied to the inner surface of the envelope and a reversely bent sheet of paper having its bight portion disposed between said wire and the closed side of said envelope and having its ends disposed between said flaps and the respective top and bottom of the envelope.

8. A file index device comprising, a backing panel, a pair of channel-shaped guides applied to said panel in parallel spaced relation and having their open sides facing each other, housing members having portions fitting within the channels of said guides and having inner sides closing portions of the open sides of said guides and provided with vertical slots therein, said housing members having flanges extending over said guides, a plurality of spring wires having their ends fitting within the slots of oppositely disposed housing members and rectangular memoranda members through which portions of said wires run and supported by said wires between said housing members, said memoranda members being adapted to be disposed in overlapped relation.

9. A file index having in combination, a backing panel, a pair of support housings applied to said backing panel and disposed in opposite parallel relation, said housings having vertical slots cut through their facing surfaces, spring wires extending between said housings and having their ends disposed within said vertical slots, said housings having notches in their upper surfaces joining said slots and memoranda members carried by said wires between said housings.

10. A filing envelope for use in a file index device, said envelope having its ends and one side closed and having its remaining side open, and having small wire-receiving openings at its two corners which join the closed ends and the closed side of the envelope, carbon transfer material applied to the inner surface of the envelope, a wire extending through said wire-receiving openings and a reversely bent sheet of paper having its bight portion disposed between said wire and the closed side of the envelope.

In testimony whereof I affix my signature.

JOSEPH M. HURLEY. 115
